(57) CLAIM

The ornamental design for footwear, as shown and described.

DESCRIPTION

FIG. 1 is a bottom perspective view of footwear showing my new design.

FIG. 2 is a front view of the design.

FIG. 3 is a back view of the design.

FIG. 4 is a view of the design from the right side.

FIG. 5 is a view of the design from the left side; and,

FIG. 6 is a bottom view of the design.

The broken lines showing portions of an item of footwear in FIGS. 1-6 are for illustrative purposes only and form no part of the claimed design.
